UNITED STATES PATENT OFFICE

LOUIS R. WILLIAMS, OF LOS ANGELES, CALIFORNIA

GROOVING MACHINE

Application filed January 16, 1929. Serial No. 332,923.

My invention relates to and has for a purpose the provision of a simple, substantial and compact machine by which a surface, such as the surface of a monolithic cement 5 slab or floor for example, can, with the utmost ease and dispatch, be grooved in a manner to simulate tiling so that the appearance of the surface to the eye will be that of a floor constructed of separate and 10 distinct tiles.

It is a further purpose of my invention to provide a grooving machine of the above described character by which a groove of uniform depth will be produced in a surface 15 irrespective of inequalities or unevenness in the contour of the surface so that such defects will not be detectable from an observation of the grooves.

It is another purpose of my invention to 20 provide a grooving machine which is adjustable with the utmost ease and dispatch, to produce grooves of different depths in a surface so that the tiled effect of the grooved surface will be more or less pronounced, to 25 conform in a predetermined proportion with the particular size of tiles represented, as well as to conform or harmonize with the architectural scheme of a particular installation.

It is still another purpose of my invention to provide a grooving machine embodying a carriage for supporting a grooving element for movement over a surface along a predetermined path, to cause the grooving 30 element to produce a groove in the surface, with mechanism by which the carriage and grooving element can be elevated clear 35 of the surface and the machine supported for movement from place to place, all in 40 such manner as to render the machine conveniently portable and capable of being maneuvered with the utmost ease and dispatch from one location on the surface to another, thereby greatly facilitating the 45 grooving operations.

I will describe only one form of grooving machine embodying my invention, and will then point out the novel features thereof in claims.

50 In the accompanying drawings,

Fig. 1 is a view showing in side elevation and in working position, one form of grooving machine embodying my invention,

Fig. 2 is a view in front elevation of the grooving machine shown in Fig. 1;

Fig. 3 is a plan sectional view taken on the line 3—3 of Fig. 1 and looking in the direction of the arrows;

Fig. 4 is a vertical sectional view taken on the line 4—4 of Fig. 3 and looking in the direction of the arrows;

Fig. 5 is an enlarged detail sectional view taken on the line 5—5 of Fig. 1 and looking in the direction of the arrows.

Fig. 6 is a fragmentary detail sectional view taken on the line 6—6 of Fig. 5 and looking in the direction of the arrows.

Fig. 7 is a detail sectional view taken on the line 7—7 of Fig. 3 and looking in the direction of the arrows, and

Fig. 8 is a fragmentary sectional view taken on the line 8—8 of Fig. 7 and looking in the direction of the arrows.

Referring specifically to the drawings in which similar reference characters designate similar parts in each of the several views, my invention in its present embodiment comprises a carriage C including a rectangular frame 10, and wheels 11, 12 and 13 journaled in the frame and co-operating to support the frame for rolling movement over a floor. The wheels 11 and 12 are disposed one in advance of the other and their peripheries are grooved to ride upon a track T which broadly constitutes a means for guiding the carriage along a predetermined path over the floor.

The carriage C supports a grooving element G and a driving means for the element in the present instance in the form of an electric motor M, the grooving element being rotatably mounted on a support S in the form of a platform 14 pivotally mounted on the carriage for movement vertically by means of pins 15 extending through lugs 16 and 17 formed respectively on the platform and frame 10. The motor is secured directly to the platform by means of threaded studs 18 extending through feet 19 formed on the motor housing and threaded into the

platform, and is operatively connected to the grooving element by means of a driving gear 20 fixed to the motor shaft 21 and meshing with a driven pinion 22 fixed to a horizontal stub shaft 23 journaled in the lower section 24 of a two section housing 25 secured to a lateral extension 25^a of the platform 14 by bolts 26.

The upper section 27 of the housing 25 is detachably secured to the lower section 24 by screws 28 and co-operates with the lower section to enclose the gear 20 and pinion 21 and provide a reservoir for containing a quantity of lubricant so that the gears will operate in a bath of lubricant.

The grooving element G in the present instance is shown in the form of a grinding disk 29 of abrasive material such as carbide and is clamped axially on the forward end of the stub shaft 23 exteriorly of the housing 25, between a pair of collars 30, by means of a nut 31 threaded on the stub shaft.

It will be clear that due to the pivotal mounting of the platform 10, the weight of the latter and motor as well as the weights of all other parts supported by the platform operate to normally urge the disk 29 downwardly against the floor so that upon rotation of the disk and movement of the carriage on the track T, a groove will be produced in the floor.

In order to definitely limit the downward movement of the platform and hence of the disk 29, a gaging means is provided which in the present instance comprises a rectangular frame 32 (see Figs. 1, 5 and 6) slidably mounted for movement vertically in grooves 33 formed in the lower section 24 of the housing 25, and having mounted for oscillating movement on the lower end thereof by means of a pin 34, a frame 35 in which is journaled one in advance of the other a plurality of gaging rollers 36 which in the present instance are shown as being three in number, the center roller being mounted on the pin 34 and the other two rollers on pins 37 carried by the frame 35 at opposite sides of the pin 34.

The frame 32 is normally locked against vertical sliding movement in the grooves 33 by means of a shaft 38 threaded into the lower section 24 of the housing 25 and journaled in the frame 32, the shaft having a collar 39 fixed thereto and abutting the top horizontal member 40 of the frame 32.

The rollers 36 are adapted to roll in unison directly on the surface of the floor, and function to support the platform 14 to the extent of definitely limiting the downward pivotal movement of the platform on the carriage. As the disk 29 moves bodily with the platform, it will be clear that as the carriage is traveling on the track T the rollers 36 will follow any inequalities in the

surface of the floor and thus raise the platform and permit the latter to lower in accordance with the inequalities of the surface, so that the disk 29 will accordingly be raised or lowered and thus insure that a fixed relationship will be maintained between the disk and surface of the floor irrespective of inequalities in the contour of the surface, thereby causing a groove of uniform depth to be produced by the disk. This uniformity of depth is maintained even when the grinding disk is in a position for cutting a groove at an angle to a groove already cut, for two of the rollers always form a support, so that the third roller may be directly above the previously cut groove without being liable to gravitate into it, and that thus the cutting to a required depth of a groove transversely to the previously cut groove is not affected by the latter. On the contrary, if, instead of the plurality of rollers 36, only one such roller were journaled in the frame 35, a groove of a uniform depth could not be cut across another groove by the disk. Because of the plurality of rollers 36, my grooving machine has therefore a particular advantage over similar machines which depend upon only one roller for maintaining the grooving element in a lowered position.

The shaft 38 provides a means by which vertical adjustment of the gaging rollers 36 can be effected relative to the disk 29 so as to vary the depth of groove produced in the floor by the latter. According as the shaft 38 is rotated by a suitable tool (not shown) in one direction or the other, the frame 32 and hence the frame 35 with its rollers 36 will be raised or lowered bodily so that the positions of the rollers vertically with respect to the disk will be varied, and hence the depth to which the disk can cut, accordingly varied.

The effective total weights of the platform, motor and all other parts supported by the platform, which impose a downward pressure of the disk 29 against the floor can be varied, and to this end a coiled expandable spring 41 is connected at its lower end to the platform and at its upper end to an adjusting screw 44 threaded into a horizontal member 45 of a bracket 46 having upright members 47 secured to the carriage C at one side of the latter to support the bracket from the carriage. The adjusting screw 44 is provided with a handle 44^a by means of which the screw can be rotated in one direction or the other to increase or decrease the tension of the spring and hence vary the strength of the latter so that the spring will exert a greater or less upward lifting force upon the platform in opposition to the weight of the platform and parts supported thereon. The pressure of the disk 29 against the floor will thus be varied in ac-

cordance with a variation in the strength of the spring 41.

The bracket 46 co-operates with a similar bracket 48 secured to the other side of the carriage, and a base plate 49 secured to and spanning the brackets to provide a superstructure on which is supported a rotary suction fan 50, the rotor of which is driven from the motor M by means of a belt 51. Trained over a pulley 52 fixed to the rotor shaft 53 and a second pulley 54 fixed to the motor shaft 21. The belt is maintained under driving tension at all times, irrespective of the raising and lowering movement of the platform 14, by means of an idler pulley 55 rotatably mounted on an arm 56 pivoted at 57 on the stator of the fan 50 and normally urged into engagement with one stretch of the belt 51 by means of a spring 58 connected to the arm and to the bracket 46.

The intake 59 of the fan 51 is connected to a conduit 60 having a flexible section 61 connected to a hood 62 enclosing the disk 29 and secured to the oscillating frame 35, the hood being provided on its outer side with a door 63 to permit access to the disk for removal and replacement of the latter.

To the exhaust 64 of the fan is connected a conduit 65 leading to a circular header 66 supported in elevated position from the brackets 46 and 48 by means of rods 67, and from the header is suspended a bag 68. It will be clear that during the grooving operation, the material as removed from the floor by the disk 29 will be sucked by the fan 51 from the interior of the hood 62 and discharged into the bag so that all dust is eliminated and the possibility of the removed material interfering with the proper cutting of the groove, prevented.

The carriage C and the grooving element G are capable of being elevated clear of the floor and supported for rolling movement over the floor in a direction at a right angle to the direction of travel of the carriage along the track T so that the carriage can be applied to or removed from the track as desired. To this end and as a means for accomplishing these functions, a rock shaft 69 is journaled horizontally in one end of the carriage C at right angles to the axes of the wheels 11, 12 and 13 and projects from opposite sides of the carriage. To the projecting ends of the shaft 69 are fixed arms 70 and 71, on the free ends of which are rotatably mounted rollers 72 and 73 respectively so that the rollers will be lowered or elevated according as the shaft 69 is rocked in one direction or the other.

A second rock shaft 74 is journaled horizontally in the opposite end of the carriage parallel to the shaft 69, and to this shaft is fixed an arm 75 to the free end of which is pivotally connected a second arm 76 carry-

ing a roller 77 and guided for vertical movement in recess 78 in the carriage by means of a pin 79 on which the roller 77 is rotatably mounted, and a slot 80 in a wall of the recess, slidably receiving one projecting end 70 of the pin. Thus the roller 77 will be lowered or elevated according as the shaft 74 is rocked in one direction or the other.

The rollers 72, 73 and 77 are capable of being simultaneously lowered to elevate the carriage C clear of the floor and track T, and support the carriage for rolling movement, or simultaneously elevated to lower the carriage to the floor and track by means of an operating lever 81 fixed to the shaft 74 and connected by a link 81^a to an angular extension 82 on the arm 70, and the rollers are capable of being latched in their lowered or active positions by means of a gravity pawl 83 pivoted at 84 on the link and engageable with a notch 85 formed in the carriage in the plane of the pawl. The pawl is provided with an angular extension 86 by means of which the pawl can be released from the notch to permit lowering of the carriage.

To the rock shaft 69 are fixed at points between the wheels 11 and 12 a pair of arms 87 and 88, the free ends of which underlie the ends of the oscillating frame 35, and are engageable with the frame to raise the latter and hence the platform and grooving element G as the shaft 69 is rocked to elevate the carriage C, so that both the latter and grooving element will be simultaneously elevated and the machine rendered capable of being rolled over the floor towards and away from the track.

To one of the upright members 47 of the bracket 46 is pivoted at 89 a handle 90 by means of which the carriage can be pushed over the floor during the grooving operation, and on the base plate 49 is secured a socket 91 from which conductors 92 lead to the motor. A suitable plug carried by 110 a flexible conductor (not shown), leading from a source of current supply is adapted to be plugged into the socket to supply current to the motor M.

The operation of the machine is as follows:

Let it be assumed that a cement floor, for example, is to be grooved in a manner to simulate tiling. A suitable length of track T is placed on the floor parallel to the length of a groove to be produced so that when the carriage C is rolled over the floor on the rollers 72, 73 and 77 and then lowered to position the wheels 11 and 12 on the track, the grooving element G will be disposed in the plane it is desired to produce the groove in the floor, and the gaging rollers 36 will rest on the floor alongside the track.

With the carriage applied to the track T

and assuming that the vertical adjustment of the gaging rollers 36 is such that the grooving element will clear the floor, current is supplied to the motor M, after which 5 vertical adjustment of the rollers 36 in an upward direction is effected by rotation of the shaft 38 until the platform 14 and hence the grooving element G are lowered sufficiently for the latter to produce a groove 10 of the depth desired. The carriage C is then pushed along the track by the handle 90 to cause the grooving element to produce a groove in the floor parallel to the track T. After the cutting of a groove in the floor, 15 the carriage is elevated from the floor and track, and the grooving element from the floor, by proper manipulation of the operating lever 81, so that the track can be removed and replaced in another location on 20 the floor for the cutting of another groove. It will be clear that the operation above described is repeated for each groove to be produced and that the machine is capable of being readily moved about to produce the 25 desired grooves as well as transferred from place to place between the grooves so that the grooving of the floor in simulation of tiling can be accomplished with the utmost ease and dispatch.

30 Although I have herein shown and described only one form of grooving machine embodying my invention, it is to be understood that various changes and modifications may be made herein without departing 35 from the spirit of the invention and the spirit and scope of the appended claims.

I claim as my invention:

1. A grooving machine comprising a carriage, means for guiding the carriage along a predetermined path over a floor, a support pivotally mounted on the carriage for movement vertically, a grooving element rotatably mounted on the support eccentrically of the pivotal mounting of the latter 45 and normally urged by the support into engagement with the floor, to produce a groove in the latter in response to movement of the carriage over the floor, and means for limiting the movement of the support towards the floor to control the depth of the groove produced in the floor by the element, said last means comprising a frame mounted for oscillating movement on the support, and a plurality of gaging rollers journaled 50 one in advance of the other in the frame and adapted to bear in unison directly upon the floor, the axis of the grooving element being intermediate the axis of the foremost and rearmost rollers.
- 60 2. A grooving machine comprising a wheeled carriage, a track for guiding the carriage along a predetermined path over a floor, a platform pivotally mounted on the carriage, a grinding disk rotatably mounted on the platform eccentrically of the pivotal mounting of the latter, a motor supported by the platform for driving the grinding disk, the weights of the platform and motor being operable to urge the disk downwardly, a frame mounted for oscillating movement on the platform, and a plurality of gaging rollers journaled one in advance of each other in the frame and adapted to roll in unison directly on the floor to support the platform, the axis of the grinding wheel being intermediate the axis of the foremost and rearmost rollers.
- 65 3. A grooving machine comprising a wheeled carriage, a track for guiding the carriage along a predetermined path over a floor, a platform pivotally mounted on the carriage, a grinding disk rotatably mounted on the platform eccentrically of the pivotal mounting of the latter, a motor supported by the platform for driving the grinding disk, the weights of the platform and motor being operable to urge the disk downwardly, a frame mounted for oscillating movement on the platform, and a plurality of gaging rollers journaled one in advance of each other in the frame and adapted to roll in unison directly on the floor to support the platform, the axis of the grinding wheel being intermediate the axis of the foremost and rearmost rollers.

mounting of the latter, a motor supported by the platform for driving the grinding disk, the weights of the platform and motor being operable to urge the disk downwardly, a frame mounted for oscillating movement on the platform, and a plurality of gaging rollers journaled one in advance of each other in the frame and adapted to roll in unison directly on the floor to support the platform, the axis of the grinding wheel being intermediate the axis of the foremost and rearmost rollers.

3. A grooving machine comprising a wheeled carriage, a track for guiding the carriage along a predetermined path over a floor, a platform pivotally mounted on the carriage, a grinding disk rotatably mounted on the platform eccentrically of the pivotal mounting of the latter, a motor supported by the platform for driving the grinding disk, the weights of the platform and motor being operable to urge the disk downwardly, a frame mounted for oscillating movement on the platform, and a plurality of gaging rollers journaled one in advance of each other in the frame and adapted to roll in unison directly on the floor to support the platform, the axis of the grinding wheel being intermediate the axis of the foremost and rearmost rollers.

4. A grooving machine comprising a wheeled carriage, a track for guiding the carriage along a predetermined path over a floor, a platform pivotally mounted on the carriage, a grinding disk rotatably mounted on the platform eccentrically of the pivotal mounting of the latter, a motor supported by the platform for driving the grinding disk, the weights of the platform and motor being operable to urge the disk downwardly, a frame mounted for oscillating movement on the platform, and a plurality of gaging rollers journaled one in advance of each other in the frame and adapted to roll in unison directly on the floor to support the platform, and means whereby the frame can be adjusted vertically relatively to the platform.

5. A grooving machine comprising a wheeled carriage, a track for guiding the carriage along a predetermined path over a floor, a platform pivotally mounted on the carriage, a grinding disk rotatably mounted on the platform eccentrically of the pivotal mounting of the latter, a motor supported by the platform for driving the grinding disk, the weights of the platform and motor being operable to urge the disk downwardly, a frame mounted for oscillating movement on the platform, and a plurality of gaging rollers journaled one in advance of each other in the frame and adapted to roll in unison directly on the floor to support the platform, and means whereby the frame can be adjusted vertically relatively to the platform, comprising an adjusting screw coacting with the frame and platform to raise or lower the latter according as the screw is rotated in one direction or the other.

6. A grooving machine comprising a wheeled carriage, a track for guiding the carriage along a predetermined path over a floor, a platform pivotally mounted on the carriage, a grinding disk rotatably mounted on the platform eccentrically of the pivotal mounting of the latter, a motor supported by the platform for driving the grinding disk, the weights of the platform and motor being operable to urge the disk downwardly, a frame mounted for oscillating movement on the platform, a plurality of gaging rollers journaled one in advance of each other in the frame and adapted to roll in unison directly on the floor to support the platform, the axis of the grinding wheel being intermediate the axis of the foremost and rearmost rollers.

directly on the floor to support the platform, and means for elevating the carriage and platform sufficiently to clear the carriage from the track and the grooving element 5 from the floor, and including rollers for supporting the carriage for rolling movement over the floor in a direction at an angle to the direction of travel of the carriage on the track, arms on which the rollers are 10 rotatably mounted, rock shafts to which the arms are fixed, a link operatively connecting the rock shafts, an operating member co-acting with the link to rock said shafts and thereby raise or lower the rollers, and means 15 for releasably retaining the rollers in lowered position.

6. A machine of the character described comprising a wheeled carriage, a track for guiding the carriage along a predetermined 20 path over a floor, grinding means supported by the carriage for grinding engagement with the floor, and means for elevating the carriage sufficiently to clear it from the track and the grinding element from the 25 floor, including rock shafts mounted on the carriage, arms fixed to the shafts, rollers carried by the arms for supporting the carriage for rolling movement over the floor in a direction at an angle to the direction of 30 travel of the carriage on the track, a link operatively connecting the shafts, an operating member coacting with the link to rock the shafts and thereby raise or lower the rollers, and means for releasably retaining 35 the rollers in lowered position.
